STEAM GENERATING, SUPERHEATING AND REHEATING UNIT WITH REHEATER AHEAD OF THE SUPERHEATER

Paul H. Koch, Bernardsville, N. J., assignor to The Babcock & Wilcox Company, New York, N. Y., a corporation of New Jersey

Application November 30, 1955, Serial No. 550,063

1 Claim. (Cl. 122—478)

This invention relates to the combined generation, superheating, and reheating of high pressure and high temperature steam adapted for use in efficiently producing power in a power plant involving a plural stage steam turbine.

The invention is exemplified in an integrated unit involving a high temperature furnace, with the gases from the furnace first passing over the heat absorbing surfaces of a reheat before passing over the heat absorbing elements of a high temperature superheater receiving steam from steam generating tubes connected into a fluid circulation system and disposed as wall tubes along the boundary surfaces of the furnace, and a gas recirculation system withdrawing low temperature gases from a point in the gas flow beyond the superheater and introducing those gases into the furnace at a point near the reheat for control of the gas temperatures contacting the reheat.

The invention will be concisely set forth in the claim, but for a complete understanding of the invention, its uses, and advantages, recourse should be had to the following description which refers to the accompanying drawings in which a preferred embodiment of the invention has been illustrated.

In the drawings:

Fig. 1 is a sectional side elevation of a steam generating, steam reheating and, steam superheating unit embodying the invention; and

Fig. 2 is a horizontal section on the section line 2—2 of Fig. 1.

The drawings show a cyclone furnace 10 of a type, the details of which are illustrated and described in the patent to Kerr et al. 2,594,312. This cyclone furnace burns a slag forming fuel, such as particle form coal at temperatures substantially above the fusion temperature of the slag so that the fused slag flows to the bottom of the cyclone furnace and exits into the primary furnace chamber 12 through the slag exit opening 14. The high temperature gases with small particles of fused solids in suspension pass from the cyclone furnace chamber through its throat 16 into the primary furnace chamber 12, and then flow upwardly between and over the screen formed by the rows of tubes 18. The high temperature gases with their suspended solids thence flow into the secondary furnace chamber 20, the walls of which such as the front wall 22, the rear wall 24 and the connecting side walls 39, 41 include upright steam generating tubes connected into the fluid circulation system of the unit and normally discharging steam and water mixtures into the steam and water drum 26. These tubes are connected into the fluid circulation by the downcomer 28 and other appropriate circulatory connections with the submerged drum 30, from which extend the steam generating tubes forming or lining the above indicated walls, as well as the floor 32, and the inclined baffle wall 34 separating the primary furnace chamber 12 from the secondary furnace chamber 20. The side walls of the furnace chamber include similarly con-

2

nected steam generating wall tubes discharging at their upper ends into side wall headers 40, and leading upwardly from lower headers 42 which are appropriately connected to the downcomer 28 by circulators 44. Similar circulators 46 connect the lower end of the downcomer with cyclone furnace headers 48 and 50, into which the cyclone furnace wall tubes are connected.

In accordance with the invention, the high temperature slag-laden heating gases flowing upwardly in the 10 secondary furnace or radiation chamber 20 first contact heat absorbing surface of a steam reheat 52. The reheat has a radiant heated section formed by longitudinally spaced rows 62 and 64 of transversely spaced tube platens defined by a plurality of multi-looped nested tubes, corresponding tubes in the rows 62, 64 being series connected to provide parallel steam flow paths from the reheat inlet header 54 to an intermediate header 56. In addition to the radiant section, the reheat has a convection heated section formed by a row of U-tube platens 58 in the entrance end of the rearwardly tapering convection heating gas pass extending rearwardly from the upper end portion of the radiation chamber 20. The ends of the tubes 58 are connected to the intermediate header 56 and the reheat outlet header 60, thus providing a series flow of steam being reheated first through the reheat radiant section and then through the convection section. With this location and arrangement of the reheat heat absorbing surface, the desired high reheat temperature can be readily maintained over a relatively wide load range due to the inherently flat reheat temperature curve of serially connected radiant and convection sections.

For protection of the banks of reheat tubes 62 and 64, and to maintain effective heat transfer from the high 35 temperature gases to these tubes, the gases and their suspended fused slag particles have their temperatures lowered by the gas recirculation system including the fan 70, the fan inlet ductwork 72 communicating with the flow of heating gases at the port 74, beyond the 40 superheat, and fan outlet ductwork 76 leading through a port 78 into a recycled gas chamber 80, from which the lower temperature recycled gases flow in the direction indicated by the arrows 82 and through the openings 84 in the furnace wall 24. These openings are 45 provided by bending portions of some of the wall tubes, such as the tubes 86 (Fig. 1) out of their wall alignment. The openings 84 and the arrangement of adjoining portions of the wall tubes is clearly indicated in Fig. 2, as is the direction of flow of the recycled lower 50 temperature gases indicated by the arrows 88.

As the demand for steam increases, the rate of firing of the cyclone furnace increases, and the temperature of the gases approaching the reheat 52 tends to simultaneously and correspondingly increase. Under these 55 circumstances the rate of flow of the lower temperature recycled gases through the gas recirculation system and into the secondary furnace chamber 20 is increased in order to maintain the temperature of the gases contacting the reheat 52, within allowable limits, and to so change the temperature of the suspended particles of slag within the gases that they are not in a sticky state as they contact the heat absorbing elements of the reheat.

Under conditions of decreasing the load with a correspondingly decreasing rate of firing of the cyclone furnace 10, the rate of flow of the recycled lower temperature gases into the secondary furnace chamber 20 would be decreased, but this decrease may be modified for the purpose of affecting the temperature of the reheated steam 70 by controlling the mass flow of gases over the tubes of the reheat, and the following superheat.

The superheat has an inlet header 90 receiving,

through the circulators 92, steam separated from the steam and water mixtures within the steam and water drum 26. From the header 90 a plurality of superheater tubes lead downwardly. The first sections of these tubes are disposed in two rows 92 and 94. The tubes next lead through the roof sections 96 and 98 of the downflow convection gas pass 100. These tubes lead downwardly along the gas pass walls 102 and 104 to the lower header 106. From this header the steam flows upwardly through a plurality of tubes 108, the subsequent sections of which form serially connected return bend tubes constituting the banks of tubes 110-112. The outlet ends of these tubes 114 are connected to the header 116, from which appropriate circulatory connections 118 lead to the secondary superheater header 120. From the header 120 there extends a row of tubes having serially connected return bend sections forming the bank of secondary superheater tubes 122. From the outlet section of this bank of tubes these tubes pass horizontally between successive upright superheater tubes leading from the header 90 and between the steam generating tubes extending upwardly from the wall 24 to the drum 26. From a bank of tubes 124 the tubular sections extend as an additional bank of tubes 126, the outlet ends of which are connected to the outlet header 128 of the secondary superheater. From this header the high temperature steam passes to the high pressure and high temperature section of a steam turbine, or another appropriate point of use.

The high temperature gases after having passed over the banks of tubes 62 and 64 of the re heater pass across the above described banks of tubes of the superheater, and then across the bank of tubes 130 connected to the inlet and outlet headers 132 and 134 of the economizer into the duct-work above the hopper 134, from which a duct or flue 136 leads past the recycled gas port 74 to a flue or stack.

The steam generating, superheating, and reheating unit of the invention is preferably provided with such a control system that, as the demand for steam and the fuel firing rate increase, the flow of recycled gases into the furnace chamber increases. Reversely, as the load decreases and as the firing rate decreases, there will be a decrease in the flow of recycled gases. That part of the control system affecting the flow of recycled gases may function from a plurality of operative variables such as representations of gas temperature at a position in the secondary furnace chamber and close to the re heater. Other variables from which the flow of recycled gases is controlled may include representations of the fuel burning rate. The control system would involve known control components such as those indicated in the control system of the common assignee's co-pending application, Serial Number 250,268, filed in October 3, 1951. Other variables influencing the control system may be representatives of reheat and superheat steam temperature or temperatures. The control system of the illustrative unit may also involve such controls of the recycled gas system as are indicated in the common assignee's co-pending applications to Moonan 542,927,

Troutman 542,925, and Stallkamp 542,926, filed October 26, 1955 for so controlling the operation of the recycled gas system and more particularly the gas flow in the vicinity of the recycled gas fan that reverse flow of gases from the furnace chamber toward the recycled gas fan is prevented.

Although the invention has been described with reference to the details of a preferred embodiment, it is to be recognized that the invention is not limited to all the details thereof. It is rather to be considered as of a scope commensurate with the scope of the subjoined claim.

What is claimed is:

A vapor generating, superheating and reheating unit 15 comprising walls defining a vertically elongated radiation chamber having a laterally extending convection heating gas pass opening to the upper end thereof and a downflow gas pass connected to the opposite end of said convection gas pass, vapor generating tubes lining the 20 walls of said radiation chamber, a cyclone furnace for burning a slag-forming particulate fuel in suspension at temperatures above the fuel ash fusion temperature and causing slag-carrying high temperature heating gases to enter the lower end of said radiation chamber and 25 flow upwardly in said radiation chamber, a row of pendent tube platens in the upper part of said radiation chamber arranged to receive heat mainly by radiation and forming a radiant vapor reheating section, a second row of pendent tube platens in said convection heating 30 gas pass arranged to receive heat mainly by convection and forming a convection vapor reheating section, a group of secondary vapor superheating tubes in said convection heating gas pass rearwardly of said convection vapor reheating section, a group of primary vapor 35 superheating tubes in said downflow gas pass serially connected to said secondary vapor superheating tubes, all of said primary and secondary vapor superheating tubes being located in the gas flow path downstream of said convection vapor reheating section, a group of 40 economizer tubes in said downflow gas pass below said primary vapor superheating tubes, means forming a series of transversely spaced gas inlet ports in one of the vertical walls of said radiation chamber at a level between the point of entry of the heating gases and the lower 45 end of said first row of re heater tube platens, and means for withdrawing heating gases from a point in said downflow gas pass below said economizer tubes and introducing the withdrawn gas into said radiation chamber through said gas inlet ports.
